UNITED STATES PATENT OFFICE.

HANS NATHUSIUS, OF FRIEDENSHÜTTE, KREIS BEUTHEN, GERMANY.

ELECTRICAL FURNACE.

1,265,485.

Specification of Letters Patent.

Patented May 7, 1918.

Application filed October 5, 1914, Serial No. 865,057. Renewed March 30, 1918. Serial No. 225,850.

To all whom it may concern:

Be it known that I, HANS NATHUSIUS, a citizen of the German Empire, residing at Friedenshütte, Kreis Beuthen, Germany, 5 have invented certain new and useful Improvements in Electrical Furnaces, of which the following is a specification.

My invention relates to improvements in electrical furnaces, and more particularly in 10 furnaces which are heated by the resistance offered to the electric current passing through the lining of the wall of the furnace and through the charge, and which are closed all around in an air tight manner, which 15 is possible because heating by means of arcs by displaceable electrodes is avoided. Furnaces of this class are designed for example for carrying out metallurgical processes, for example for obtaining zinc. A furnace 20 of this class forms the subject matter of my copending application Ser. Nr. 812,209, filed January 15th, 1914. My present invention relates to an improvement of the furnace described in this application.

25 In the furnace described in the said application the electrodes which provide the terminals of the multiphase system are disposed in pairs on opposite sides of the chamber of the furnace, and there is a potential 30 difference between all the electrodes. The electrodes are so connected to the supply circuit that between pairs of oppositely arranged electrodes there is the maximum potential difference, *i. e.* the non-interlinked 35 phase voltage, which corresponds to the maximum resistance between the said electrodes. However, between electrodes which are immediately adjacent to each other there is a potential difference of

$$40 \frac{1}{2} \text{Ep.} \sqrt{3} = 0.866 \text{ Ep.}$$

which is higher than the potential difference between two electrodes which are obliquely opposite to each other, and which 45 are at a greater distance away from each other, the potential difference between these electrodes being only 0.5 Ep. Therefore there is no uniform flow of current between the electrodes, and the heating effect between 50 adjacent electrodes is higher than between electrodes which are obliquely opposite each other.

The object of the improvements is to dispose the electrodes in such a way, that the 55 current and the heating effect are uniform

throughout the heating chamber. With this object in view my invention consists in disposing the electrodes of a series of phases in star connection or circumferentially and uniformly around the chamber, so that the 60 potential differences between the pairs of electrodes correspond to the distances thereof and the resistances between the same. Thereby the heating effect on the charge and lining of the furnace is perfectly uniform. 65 The invention can be carried out in different ways. In one embodiment the electrodes are parallel to the longitudinal axis of the furnace and extend from one end to the other of the chamber, in which case the potential 70 differences between the electrodes are proportional to the relative distances of and the resistances between the same.

If the furnace is not uniformly charged, or the conductivity of the charge is not uniform in all the zones, it may happen, that the current does not flow through the chamber uniformly over the whole length of the same. In order that also in such cases the flow of the current through the charge be 80 uniform, the secondary windings of a transformer for multiphase or threephase current are subdivided into sectional windings and connected with electrodes which in each 85 phase series are arranged in star connection or circumferentially around the heating chamber in such a way, that not only the potential difference between the pairs of electrodes corresponds to the distance of and the resistance between the electrodes, but 90 that also between adjacent sets of electrodes there is the proper potential difference, so that the current must necessarily be uniform between adjacent sets of electrodes. By thus 95 arranging the electrodes I am enabled to adapt the current flowing between the electrodes of one or more series of phases to different conditions by regulating the current supply to the series of phases by means of potential regulation. The construction is 100 further preferable for the reason, that comparatively short electrodes are used, so that the walls of the furnace are not destroyed by expansion of the electrodes being heated, as is the case where long electrodes are provided. 105

For the purpose of explaining the invention an example embodying the same has been shown in the accompanying drawings, in which the same letters of reference have 110

been used in all the views to indicate corresponding parts. In said drawings—

Figure 1, is a longitudinal section of the furnace taken on the line 1—1 of Fig. 2,
5 Fig. 2, is a cross-section of the furnace taken on the line 2—2 of Fig. 1 and showing the position of the electrodes,

Fig. 2^a, is a diagram illustrating the flow of the currents and the potential differences 10 between the electrodes,

Fig. 3, is a diagrammatical view illustrating a modification of the furnace, and

Fig. 4, is a longitudinal section through the furnace according to Fig. 3. For clearness sake the sets of electrodes are shown as 15 being disposed in the same planes. I wish it to be understood that the invention is not limited to the number of electrodes shown in the figures, and that any desired number of 20 sets of electrodes can be provided. In all the cases the electrical connection is alike in principle, and the number of the sections of the secondary of the transformer corresponds to the number of the sets of electrodes, or a corresponding multiphase current 25 is supplied to the electrodes.

Referring to the example illustrated in Figs. 1, 2, and 2^a, the chamber A of the furnace is closed all around, the electrodes do 30 not project into the heating chamber and are covered by a lining having a suitable electrical resistance.

In some cases, for example, where the ends of the electrodes are not liable to be 35 destroyed by melting or destruction by the charge or by the chemical agents produced in the process, and the charge can not be made impure by the electrodes, the electrodes can project into the melting chamber.

40 In the example shown in Figs. 1, 2, and 2^a six electrodes E are uniformly distributed around the circumference of the heating chamber, and the electrodes are disposed in pairs diametrically opposite each other and connected to the source of electric current. 45 As appears from Fig. 1 the current flows through the apparatus in the following way: If E_p is the phase voltage, the potential difference between opposite electrodes 50 E_1 and E_1' , E_2 and E_2' , and E_3 and E_3' is always E_p , and the potential differences of the other electrodes appear from the following table:

$$55 \quad \begin{array}{l} \left| \begin{array}{l} 1-2 \\ 1-3 \\ 2-3 \\ 1'-2' \\ 1'-3' \\ 2'-3' \end{array} \right| = \frac{E_p \sqrt{3}}{2} = 0.866 E_p. \quad \begin{array}{l} \left| \begin{array}{l} 1-2' \\ 1-3' \\ 2-3' \\ 2-1' \\ 3-1' \\ 3-2' \end{array} \right| = 0.5 E_p. \end{array} \end{array}$$

As appears from Fig. 1, the electrodes extend over the whole length of the chamber 60 A which is connected in the usual way with one or more receivers or condensers B.

Where electrodes of considerable length are objectionable, similar electrical connections can be used in connection with 65 six phase current or three-phase current with

the proper subdivision of the secondaries and with several sets of electrodes located one behind the other, as is shown in Figs. 3 and 4. The electrodes which have been indicated by the numerals 1, 2, 3, 1', 2', 3' correspond as to their position and arrangement to the electrodes of the furnace shown in Figs. 1, 2 and 2^a to which corresponding letters have been applied. Below the said electrodes there is a corresponding set of 70 electrodes I, II, III, I', II', III', which are likewise connected to the secondaries of their transformer in such a way, that between opposite electrodes I and I', II and II', and III and III' there is the full phase voltage, 80 while between the other pairs of electrodes there are the following potential differences:

$$85 \quad \begin{array}{l} \left| \begin{array}{l} I-II \\ I-III \\ II-III \\ I'-II' \\ I'-III' \\ II'-III' \end{array} \right| = \frac{E_p \sqrt{3}}{2} = 0.866 E_p. \quad \begin{array}{l} \left| \begin{array}{l} I'-II \\ I'-III \\ II'-III \\ II'-I \\ III'-I \\ III'-II \end{array} \right| = 0.5 E_p. \end{array} \end{array}$$

Apart from this there is a potential difference between the electrodes of one set and the electrodes of the other set, so that the charge is traversed by heating currents of 90 uniform intensity and, apart from this, is surrounded by a uniform net of current lines which traverse the lining covering the ends of the electrodes so as to heat the same.

The supply of electric energy to the individual sets of electrodes or series of phases can be automatically controlled by suitable means such as potential regulators.

I claim:

1. A closed electric furnace having a heating or reducing chamber whose walls are composed of electrically resistant material which is electrically conductive when heated, said walls having fixedly embedded in an air tight manner outside of the chamber 100 electrodes symmetrically disposed at the circumference of the chamber parallel to its axis which project over the whole length of the chamber and a source of multiphase current connected with said electrodes in such 105 a way, that the potential differences between any of the electrodes correspond to the distance and the resistance between such electrodes.

2. A closed electric furnace having a heating or reducing chamber whose walls are composed of electrically resistant material which is electrically conductive when heated, said walls having fixedly embedded in an air tight manner outside of the chamber a 115 plurality of annular disposed sets of electrodes disposed symmetrically at the circumference of the chamber parallel to its axis and a source of multiphase current connected with said electrodes in such a way 120 that the potential differences between any of the electrodes correspond to the distance and the resistance between such electrodes and that there is also potential difference 125 between the adjacent sets of electrodes. 130

3. A closed electric furnace having a heating or reducing chamber whose walls are composed of electrically resistant material which is electrically conductive when heated, 5 said walls having fixedly embedded in an air tight manner outside of the chamber a plurality of annular disposed sets of electrodes disposed symmetrically at the circumference of the chamber parallel to its 10 axis, said annular sets of electrodes being connected with as much subdivisions of the secondary windings of a source of multi-phase current as there are annular sets of electrodes in such a way that the potential differences between any of the electrodes correspond to the distance and the resistance between such electrodes and that there is also potential difference between the adjacent sets of electrodes. 15

In testimony whereof I affix my signature 20 in presence of two witnesses.
